UNITED STATES PATENT OFFICE.

GILBERT H. POOR, OF MILWAUKEE, WISCONSIN.

SAFETY LIQUID-DISPENSING APPARATUS.

1,376,226.

Specification of Letters Patent.

Patented Apr. 26, 1921.

Application filed June 12, 1920. Serial No. 388,553.

To all whom it may concern:

Be it known that I, GILBERT H. POOR, a citizen of the United States, residing at Milwaukee, in the county of Milwaukee and State of Wisconsin, have invented certain new and useful Improvements in Safety Liquid-Dispensing Apparatus, of which the following is a specification.

This invention has for its object the provision of an improved apparatus for the safe dispensation of such highly combustible liquids as gasoline.

A further object is the provision of such dispensing apparatus as will effect the dispensing and dispensation of the liquid fuel by the introduction into the closed fuel storage tank of a quantity of water or other liquid of greater specific gravity than the fuel, the quantity of fuel dispensed being conveniently and accurately regulated by utilization of a novel water container of predetermined capacity connected with the storage tank and having its communication therewith controlled by a valve.

25. A further object is the provision, in an apparatus of this character, of a novel construction of plug for connection with the storage tank through which the water is conducted to the tank and the liquid dispensed therefrom.

With these and other objects in view, the invention consists in certain novel features of construction as hereinafter shown and described and then specifically pointed out in the claims, and in the drawings illustrative of the preferred embodiment of the invention.

Figure 1 represents a side elevation, partly in section illustrating the invention applied to a storage tank.

Fig. 2 represents an enlarged sectional view through the plug detached from the container and tank.

Fig. 3 represents a top plan view of the plug.

Fig. 4 represents a bottom plan view thereof, and,

Fig. 5 is a horizontal sectional view on the line 5—5 of Fig. 2.

Referring to the drawing in detail, wherein similar reference numerals designate corresponding parts throughout the several views, the numeral 5 indicates a conventional type of liquid fuel storage tank provided in one end with an opening 6 through which the fuel is introduced and dispensed.

The apparatus for facilitating dispensation of the contents of a tank of this type consists of a plug 7 provided with an externally threaded body portion of such size 60 as to snugly fit the opening 6 and having mounted for adjustment thereon a jam nut 8 which is adapted to be advanced against the top of the tank to rigidly maintain the plug 7 in an upright position thereon. The 65 flange 9 of the plug at the upper end of the latter and the nut 8 are preferably provided with radial recesses to accommodate the jaws of a spanner wrench for convenience in adjustment of these parts. The plug 7 is provided with a longitudinal bore 10 which is restricted at its upper terminal as at 11 and provided with two separate sets of screw threads 12 and 12^a. The lowermost screw threads 12 receive the threaded upper terminal 70 of a water discharge pipe 13 the lower terminal of which is turned upwardly as at 75 14 to insure against the admission of liquid fuel thereto.

The uppermost screw threads 12^a cooperate 80 with the threaded extremity of a sectional vertical water pipe 15 between the sections of which is interposed a water controlling valve 16 equipped with a conveniently operable hand wheel 17 whereby the 85 passage of water through the pipe 15 may be conveniently controlled.

A water container 18 having a predetermined capacity is secured upon the flanged collar 19 secured to the upper terminal of 90 the section shaft 15 and is adapted to receive a quantity of water which is conducted to the interior of the storage tank 5 through the pipes 15 and 13.

The plug 7 is provided with a second bore 95 or passage 20 extending obliquely to and communicating at its lower terminal with the bore 10 and having screw threads 21 in its upper terminal. The bore 10 being of greater diameter than the water inlet pipe 100 13, provides an annular chamber in the plug 7 communicating with the oblique passage 20 through which the liquid fuel enters the pipe 22 having connection with a discharge pipe 23 by a manually controlled valve 24. 105

The operation of the apparatus is as follows. The storage tank 5 having been filled with a quantity of gasoline or other relatively light combustible liquid is engaged by the plug 7, the threaded terminal of the latter being screwed in the opening 6 in the top of the tank and secured in position

thereon by proper adjustment of the nut 8. The valves 16 and 24 are normally maintained in closed position and when it is desired to dispense a quantity of liquid fuel 5 from the supply tank 5, a quantity of water equal to the quantity of fuel which it is desired to dispense is introduced in the container 18 and the valves 16 and 24 are subsequently opened. The container 18 has a 10 capacity of, for example, five gallons of liquid and if it is desired to dispense this amount from the tank 5 five gallons of water are introduced in the container 18. Accordingly, if it is desired to dispense ten 15 gallons from the tank 5 the container 18 is twice filled with water. When the valves 16 and 24 are opened the water in the tank 18 flows by gravity through the pipe 13 and into the tank 5 and, being of greater weight 20 than the gasoline or other combustible fuel settles to the bottom of the tank causing upward displacement of the fuel and its consequent dispensation through the bore 10, passage 20 and pipes 22 and 23. The discharge 25 of fuel from the pipe 23 may be instantly controlled by closing the valve 24, even before the entire contents of the container 18 has been admitted to the tank.

Relatively short sleeves 15^a are preferably 30 mounted upon the water supply pipe sections 15 between the valve 16 and the container 18 and between the valve 16 and the plug 9 whereby the container is rigidly maintained in upright position.

35 From the above it will be seen that I have provided a highly efficient liquid dispensing apparatus which will prevent evaporation of the gasoline, and by its novel construction eliminate all dirt and sediment from 40 the oil and in addition conforms to the rigid safety requirements of apparatus of this character. In the accompanying drawings, I have illustrated my invention embodied in one form by way of example, and which in 45 practice has been found to be highly satisfactory in obtaining the desired results. It will be obvious however that other embodiments may be adopted, and that various changes in the details of construction may 50 be resorted to by those skilled in the art without departing from the spirit and scope of the invention. It is furthermore understood that the invention is not necessarily limited or restricted to the precise elements 55 shown except in so far as such limitations are specified in the subject matter being claimed.

What I claim is:

1. In an apparatus for dispensing liquids, 60 a hollow plug, a water container, a water

outlet pipe connected with the container and extending below the hollow plug, and a dispensing pipe communicating with the plug above the discharge terminal of said outlet pipe. 65

2. In an apparatus for dispensing liquids, a plug adapted for connection with a storage tank, a water container of predetermined capacity, a pipe connected with the container extending through the plug, said plug having a dispensing passage therethrough arranged above the outlet terminal of said pipe, and a dispensing pipe connected with said passage. 70

3. In an apparatus for dispensing liquids, 75 a plug adapted for connection with a storage tank provided with a liquid conducting passage, a pipe extending through and below the plug and having an upwardly curved lower extremity, a water container 80 connected with the upper terminal of said pipe, the outlet terminal of said pipe being disposed in a plane below the passage in said plug, and a dispensing pipe communicating with the passage. 85

4. In an apparatus for dispensing liquids, a plug adapted for connection with a storage tank provided with a passage, a water outlet pipe extending through the plug and below the latter, a water container having a 90 passage connected with the pipe above the plug, a valve interposed between the container and plug, and dispensing means communicating with said passage. 95

5. In an apparatus for dispensing liquids, 100 a member adapted for connection with the filling opening of a storage tank and provided with a passage, a water supply pipe extending through the member and below the latter, a water container connected with the upper terminal of the pipe above the member, and dispensing means communicating with said passage, said passage being located above the outlet end of the water supply pipe. 105

6. In an apparatus for dispensing liquids, a plug adapted for insertion in the filling opening of a storage tank, a vertical pipe extending through the plug having an upturned lower extremity, said plug having a 110 fuel conducting passage therein located above the outlet end of the pipe, a container connected with the upper terminal of the pipe above the plug, a dispensing pipe connected with the passage, and independently adjustable valves controlling passage of liquid through said pipes. 115

In testimony whereof, I affix my signature hereto.

GILBERT H. POOR.
